RECIPROCATORY PUMP FOR SUPPLYING
LIQUID FUEL TO INTERNAL-COMBUSTION
ENGINESWilfrid Edward Walter Nicolls, Pinner, England,
assignor to C. A. V. Limited, London, EnglandApplication June 18, 1948, Serial No. 33,765
In Great Britain June 20, 1947

4 Claims. (Cl. 103—154)

1

This invention relates to reciprocating pumps for supplying liquid fuel to internal combustion engines, and has for its object to enable motion to be transmitted hydraulically to the piston of the pump in a simple and effective manner which prevents leakage of liquid fuel or air past the piston when the pump is in action.

The invention comprises in combination a hollow body part, an oil reservoir on the body part, a spring-loaded hollow piston slideable in the body part and formed between its ends with an external circumferential groove which communicates with the interior of the piston through a port or ports in the piston, valve-controlled inlet and outlet connections through which liquid fuel can flow to and from the interior of the body part under the action of the piston, a spring-loaded plunger slideable in the piston and formed near its outer end with a port or ports for establishing communication between the interior of the plunger and the reservoir when the plunger is in its outer position, and means for actuating the plunger, the arrangement being such that oil admitted through the port or ports in the plunger to the interiors of the plunger and piston can serve not only to transmit movement of the plunger to the piston, but also to fill the external groove in the piston and thereby serve as a lubricating and sealing medium.

In the accompanying drawing, the single figure represents a sectional elevation of a pump for supplying liquid fuel to internal combustion engines, constructed in accordance with the invention.

In one manner of carrying the invention into effect, a hollow body part 1 is provided on which is secured an oil reservoir 2. Slidable in a vertically arranged cylindrical sleeve 3 in the body part is a hollow piston 4 which is closed at its lower end by a plug 5 and open at its upper end. The piston is loaded by a helical spring 6 acting on the lower end of the piston. The body part is provided with any convenient inlet and outlet connections 7 and 8 through which liquid fuel can flow into and out of the body part under the action of the piston 4, these connections being controlled by any convenient non-return valves. Thus the inlet valve may comprise a disc 9 loaded by a spring 10 arranged within a housing 11 having lateral ports 12, the housing being held in position by the piston spring 6. The outlet valve may comprise a ball 13 located in a bore 14 and having a limiting stop member 15. The piston 4 is formed between its ends with an external circumferential groove 16 which communicates with

the interior of the piston through a port or ports 17 formed in the piston near its closed lower end.

Slidable in the hollow piston and extending from its upper end into the oil reservoir 2 is a hollow plunger 18 which is closed at its upper end and open at its lower end, the plunger being loaded by a helical spring 19 arranged between a head 20 on the plunger and the upper end of the sleeve 3 above mentioned. Near its upper end the plunger is formed with a port or ports 21 for establishing communication between the interior of the plunger and the reservoir 2 when the plunger is in its outer or upper position, as shown in the figure, this port or ports being closable by the upper end of the piston 4 at the commencement of the working stroke of the plunger.

Mounted in and extending from the reservoir 2 is a cam-operable lever 22 which is adapted to act on the upper end of and to actuate the plunger 18.

When the pump above described is in use, the interior of the plunger 18, that part of the interior of the piston 4 not occupied by the plunger, and the external groove 16 in the piston, are filled with oil, this being initially introduced through the port or ports 21 in the plunger. When the plunger is in its outer or upper position, the piston is in its upper or inner position in which a flange 23 on the lower end of the piston abuts against the lower end of the sleeve 3 in which the piston is slideable. In this condition the oil reservoir 2 communicates with the port or ports 17 in the plunger. When the plunger is depressed against the action of its loading spring

19 by the actuating lever 22, oil is displaced from the interior of the plunger to the reservoir until the port or ports 21 in the plunger is or are closed by the adjacent end of the piston 4, whereupon the oil entrapped in the plunger and piston serves to transmit motion from the plunger to the piston, causing liquid fuel to be delivered through the outlet connection 8. As the inner end of the plunger 18 which acts on the oil is of smaller area than the lower end of the piston 4 which acts on the liquid fuel, it follows that the pressure of the entrapped oil is greater than the pressure of the liquid fuel being discharged. Consequently the oil filling the external circumferential groove 16 in the piston serves not only as a lubricant but also as an effective sealing medium for preventing leakage of liquid fuel or air past the piston. Return movement of the plunger 18 under the action of its loading spring 19 is accompanied by return movement of the piston 4 also under the action of its loading spring

6 and this causes liquid fuel to flow into the body part through the inlet connection 1. The piston reaches its normal position (determined by contact of the flange 23 on the lower end of the piston with the lower end of the sleeve 3) before the return movement of the plunger is completed, and the completion of this movement of the plunger serves to restore communication between the plunger port or ports 21 and the reservoir 2 thereby enabling the oil in the interiors of the plunger and piston to be replenished.

The output pressure of the pump above described may be conveniently regulated by limiting the pressure that can be imposed on the entrapped oil by the plunger. For this purpose there is provided between the reservoir and the external groove in the piston a by-pass 24 containing a spring-loaded pressure relief valve 25.

It will be understood that the plunger can be actuated by any convenient means, such as a cam or tappet for example, in place of the lever described and illustrated.

By this invention there is provided means for transmitting motion hydraulically to the piston of the pump in a simple and effective manner which prevents leakage of liquid fuel or air past the piston, and which ensures adequate lubrication of the working parts.

Having thus described my invention, what I claim as new and desire to secure by Letters Patents is:

1. A reciprocatory pump for the purpose described, comprising in combination a hollow body part, an oil reservoir on the body part, a spring-loaded hollow piston slideable in the body part and formed between its ends with an external circumferential groove and with at least one port which establishes communication between the groove and the interior of the piston,

5 valve-controlled inlet and outlet connections through which liquid fuel can flow to and from the interior of the body part under the action of the piston, a spring-loaded hollow plunger 10 slideable in the piston and formed near its outer end with at least one part for establishing communication between the interior of the plunger and the reservoir when the plunger is in its outer position, the inner end of the plunger being open 15 to the interior of the piston, and means for actuating the plunger, the arrangement being such that oil admitted through the port in the plunger to the interiors of the plunger and piston can serve not only to transmit movement of the plunger to the piston, but also to fill the external groove in the piston and thereby serve as a lubricating and sealing medium.

2. A pump as claimed in claim 1, having between the body part and piston, a sleeve in which the piston is slideable, the inner end of the piston being closed and having a flange adapted to engage one end of the sleeve.

3. A pump as claimed in Claim 2 in which the plunger is provided with a head and with a loading spring interposed between the head and one end of the sleeve in which the piston slides.

4. A pump as claimed in claim 1 and having a by-pass between the reservoir and the external groove in the piston, and a spring-loaded pressure relief valve in said by-pass.

WILFRID EDWARD WALTER NICOLLS.
